UNITED STATES PATENT OFFICE

WALther BAUERSFELD, OF JENA, GERMANY, ASSIGNOR, BY MESNE ASSIGNMENTS, TO
ZEISS IKON A.-G., GOERZWERK, OF BERLIN, GERMANY

REFLECTOR FOR ILLUMINATING STREETS AND THE LIKE

Application filed December 16, 1927, Serial No. 240,537, and in Germany December 22, 1926.

The present invention relates to a reflector, which for illuminating streets and the like, is to illuminate an approximately rectangular field of the ground. It is in itself well known that a reflector, which forms a part of a body of revolution whose meridional curve is a parabola, in the focal point of which the axis of rotation is perpendicular to the axis of the parabola, emits a ray pencil of rectangular cross section. According to the invention the reflector consists of a complete, barrel-shaped, thus being approximately shaped as just mentioned, glass body of rotation. Such a reflector has the advance that it can quickly and cheaply be made. In order to render it ready for use it is then simply necessary to provide the glass body according to its destination on a part of its surface (suitably about one half of its circumference) with a reflecting layer. The non-reflecting part then forms the closing glass by which the parts to be fitted inside the reflector are protected against dust and the like.

The manufacture of the reflector as a complete, barrel-shaped glass body of rotation also offers the possibility of protecting the passers-by of the streets, illuminated by such reflectors, against being dazzled by the sources of light by frosting at least the zones concerned of the non-reflecting part of the glass body. Owing to the frosting a part of the flux of light is simultaneously dispersed which is desirable in many cases, e. g. for illuminating the house-entrances located on the street.

With a view to being able to fix the reflector without impairing the path of rays, the glass body is suitably provided at both ends with extensions, which serve for the action of a holding device. Besides, it is frequently customary, either in order to protect the reflecting layer against injury or in order to attain an invisible adaptation of the current supply main and so forth, to surround the glass body with a metal casing which extends over the reflecting part of the glass body. In that case it is suitable to construct this casing as a part of a body of rotation whose axis travels parallel to that of the glass body at a short distance. In the case of a suitable choice of

the dimensions an illuminating body, provided with the new illuminating reflector, shows no conspicuously projecting edges. For the same reason and in order to prevent the penetration of dust, moisture and so on into the glass body it is advisable to close both its ends by hoods whose meridional curves supplement the outer meridional curve of the illuminating reflector to a continuously curved, closed curve.

The annexed drawing shows a constructional example of the invention in Fig. 1 in a longitudinal section and in Fig. 2 in a cross section.

A barrel-shaped glass body *a* forms a body of rotation whose meridional curve is a parabola, in the focal point of which the axis of rotation is perpendicular to the axis of the parabola. On the glass body *a* a segment *a*¹, embracing the upper half, has a reflecting layer, while on both sides of the transparent lower half segments *a*² are frosted and a middle segment *a*³ is clear. The reflecting part of the glass body *a* is enclosed by a casing of sheet-iron, which forms a part of a body of rotation whose axis lies higher than that of the glass body *a* by an amount *c*, so as to form between the bodies *a* and *b* a hollow space *d* having a cross section of the shape of a meniscus. At the one end of the casing *b* is fitted a metal cap *e* which receives holding screws *f* for fixing the glass body *a*. These screws *f* engage in a collar *h* joined to the glass body *a* and having a constriction *g*. A similar collar *h*¹ with a constriction *g*¹ is provided at the other end of the glass body *a*. At this place the casing *b* carries a ring *i* for the reception of fastening screws *k*, and a link *l* in which the mount *m* of a closing hood *n* of glass may be swivelled. The ring *i* has a nose *o*, serving as a stop for the mount *m*, as well as an elastic hose *p* which holds fast the ring *i* if the hood be closed. The mount *m* carries a handle *q* for opening the closing hood *n*. The meridional curves of the hood *n* and the metal cap *e* supplement the outer meridional curve of the illuminating reflector to a continuously curved, closed curve.

The illuminating reflector should be pro-

vided with a carrier *r* to be fixed on the casing *b*. In order to complete this reflector to an illuminating body there is further required a glow-lamp bulb *s*, which is held by a mount *t* to be provided on the metal cap *e*. For the current supply is used a cable *u* which is to be introduced by means of a recess *v* of the casing *b* into the illuminating reflector and to be disposed in the hollow space *d*. The 10 cleaning of the illuminating body and the exchange of the glow-lamp bulb *s* may easily take place through the collar *h* after the opening of the hood *n*.

I claim:

15 Illuminating apparatus comprising a reflector, consisting of a complete, barrel-shaped glass body of rotation whose meridional curve is a parabola, in the focal point of which the axis of rotation is perpendicular to the axis of the parabola and which is provided on a part of its surface with a reflecting layer, and a metal casing, only enclosing the reflecting part of the glass body and forming a part of a body of rotation whose axis travels at a short distance parallel to the axis of the glass body.

WALTHER BAUERSFELD.
